ABSTRACT OF THE DISCLOSURE

The apparatus of this application relates to grinding machines in which a common supply of fluid under pressure is used to actuate both the traverse mechanism and the feed mechanism. After a grinding wheel has been advanced to a position to begin a grinding operation, a valve is shifted to disconnect the feed mechanism from the common supply prior to initiating the traverse movement of the work relative to the grinding wheel. The valve which disconnects the feed mechanism from the supply of fluid which continues to provide a traverse movement, acts to connect the feed mechanism with a relatively low volume supply of fluid under pressure. The lower pressure and volume are sufficient to hold the grinding wheel in grinding position and also to actuate the portion of the feed mechanism which acts through the hand wheel shaft to advance the grinding wheel a short distance at a rate suitable for grinding. Thereafter, when the traverse mechanism is reversed, a momentary increase in pressure which normally occurs at the reversal point will not be transmitted to the feed mechanism.

This invention relates to grinding machines, particularly those in which the grinding operation involves relative longitudinal and transverse movements between a workpiece and a grinding wheel.

In the normal operation of such machines, where both longitudinal and transverse movements are effected hydraulically, the hydraulic motors for effecting these movements are supplied with fluid under pressure from a common source. Since the longitudinal and transverse movements never occur simultaneously, this arrangement is inexpensive and satisfactory. One characteristic of a common supply of fluid under pressure for longitudinal and transverse movements is that at the reversal point of the longitudinal movement, there is a momentary buildup or impulse in the pressure in the system. This momentary increase in pressure occurs through the entire hydraulic system including the means for effecting the transverse movement between the workpiece and the grinding wheel. Ordinarily, this pressure impulse on the transverse moving means is not objectionable. However, for work which requires very close tolerance, this pressure impulse on the grinding wheel feed mechanism is objectionable because it may cause a grinding wheel to grind beyond the desired size.

It is, therefore, an object of the present invention to prevent undesired relative transverse movement between a grinding wheel and a workpiece at the reversal point of the longitudinal movement.

Another object is to disconnect the transverse moving means from the common supply of fluid under pressure after the grinding wheel has been advanced to operative position.

Another object is to provide means for disconnecting the transverse moving means from one source of fluid under pressure and connecting said means to another source of fluid under pressure.

The drawing is a hydraulic diagram.

The means for causing the relative longitudinal movement between a workpiece and a grinding wheel consists

2

of a cylinder 10 attached to work carriage 11. Piston 12 slidably mounted in cylinder 10 is connected through piston rods 13 and 14 and support members 15 and 16 to the machine bed 17.

5 The means for effecting the transverse movement consists of a cylinder 30 in bed 17. Piston 31 is slidably mounted in cylinder 30. Piston 31 has a piston rod 32 which, in turn, has a feed screw portion 35 with threads engaging a worm wheel 36 in grinding wheel support 40. Worm wheel 36 is mounted at the lower end of vertical shaft 37 in wheel support 40. At the top of shaft 37, there is another worm wheel 38 in operative relation with worm gear 39. Worm gear 39 is part of shaft 45 having a hand wheel 46 mounted thereon. Shaft 45 also has a pinion 47 in operative relation with rack 48. Rack 48 is also a piston rod for slow feed piston 50 slidably mounted in cylinder 51.

The means for controlling the longitudinal movement consists essentially of a reversing valve 60 and a start and stop valve 61 in valve housing 62. Start and stop valve 61 also performs the functions of cushioning the start of the longitudinal movement and by-passing the reversing valve 60 when it is desired to effect the longitudinal movement manually. An exhaust line E is connected to all points in the hydraulic system requiring drainage or exhaust. The construction and operation of valve 61 and the associated reversing valve 60 is described in detail in U.S. Patent 3,207,045, granted Sept. 21, 1965.

Operation

The operation of the machine is initiated by energizing a feed solenoid 1, shifting infeed valve 65 to the left and directing fluid under pressure from pump #1 through the selector valve 66 and then to the head end of rapid feed cylinder 30.

Rapid feed piston 31 advances the grinding wheel support 40 until said piston reaches the end of its stroke, i.e. when feed screw portion 35 engages positive stop 42.

40 At this time, the exhaust pressure from the lower end of cylinder 30, which depends on the movement of piston 31, drops to zero. This pressure has been holding valve 66 in the left-hand position and the valve 67 in the right-hand position.

45 Valve 67 is then shifted to the left by spring 68 and directs fluid under pressure from pump #2 to the head end of slow feed cylinder 51 and also to the left end of valve 66, shifting valve 66 to the right.

In its hand-hand position, valve 66 shuts off the supply of fluid under pressure from valve 65 to the head end of rapid feed cylinder 30, and connects cylinder 30 with fluid under pressure from pump #2.

50 Since piston 31 is in its most advanced position, it requires only a small volume of fluid to provide pressure to hold said piston and the grinding wheel support 40 firmly in advanced position and to advance the slow feed piston 50.

55 Disconnecting feed cylinders 30 and 51 from pump #1 makes the feed mechanism free of fluctuations in pressure which occur during the traverse movement of carriage 11, particularly at reversal.

60 After a grinding wheel has been placed in operative relation with a workpiece, the traverse movement is started by shifting lever 70 to the left and depressing valve 71. In this position, valve 71 connects pressure line 75 to direct fluid under pressure through throttle valve 76 to the left hand end of start and stop valve 61 to start the traverse movement of carriage 11.

We claim:

- 70 1. In a grinding machine,
  - (a) a feed mechanism,
  - (b) a traverse motor,

- (c) a common supply of fluid under pressure for actuating said feed mechanism and said traverse motor,
  - (d) a selector valve,
  - (e) and a valve operable when said feed mechanism is in advanced position for shifting said selector valve to disconnect said feed mechanism from said common supply of fluid under pressure. 5
2. In a grinding machine,
- (a) a feed mechanism,
  - (b) a traverse motor,
- 10
- (c) a common supply of fluid under pressure for actuating said feed mechanism and said traverse motor,
  - (d) means operable when said feed mechanism is in advanced position to disconnect said feed mechanism from said common supply of fluid under pressure, 15
  - (e) and means to connect said feed mechanism with an independent supply of fluid under pressure to hold said feed mechanism firmly in advanced position.
3. In a grinding machine,
- (a) a feed mechanism,
- 20
- (b) a traverse motor,
  - (c) a common supply of fluid under pressure for actuating said feed mechanism and said traverse motor,
  - (d) and means operable when said feed mechanism is in advanced position to disconnect said feed mechanism from said common supply of fluid under pressure, 25
  - (e) the means for disconnecting said feed mechanism from said common supply of fluid under pressure also connecting said feed mechanism with a supply of fluid under pressure separate from said common supply of fluid under pressure. 30
4. In a grinding machine,
- (a) a feed mechanism,
- 35
- (b) a traverse motor,
  - (c) a common supply of fluid under pressure for actuating said feed mechanism and said traverse motor,
  - (d) and means operable when said feed mechanism is in advanced position to disconnect said feed mechanism from said common supply of fluid under pressure, 40
  - (e) the means for disconnecting said feed mechanism from said common supply of fluid under pressure maintaining operative relation between said common supply of fluid under pressure and said traverse motor. 45
5. In a grinding machine,
- (a) a feed mechanism,
  - (b) a traverse motor,
- 50
- (c) a common supply of fluid under pressure for actuating said feed mechanism and said traverse motor,
  - (d) and means operable when said feed mechanism is in advanced position to disconnect said feed mechanism from said common supply of fluid under pressure,
- 55
- (e) and a valve operable in one position to connect said feed mechanism with said common supply of fluid under pressure and in another position to con-

- nect said feed mechanism with another supply of fluid under pressure.
6. In a grinding machine,
- (a) a feed mechanism,
  - (b) a traverse motor,
  - (c) a common supply of fluid under pressure for actuating said feed mechanism and said traverse motor,
  - (d) and means operable when said feed mechanism is in advanced position to disconnect said feed mechanism from said common supply of fluid under pressure,
  - (e) the means for disconnecting said feed mechanism from said common supply of fluid under pressure being a valve operable in one position to connect said feed mechanism and said traverse motor with said common supply of fluid under pressure and in another position to connect said feed mechanism with another supply of fluid under pressure while maintaining the connection between said common supply of fluid under pressure and said traverse motor.
7. In a grinding machine,
- (a) a feed mechanism,
  - (b) a traverse motor,
  - (c) a common supply of fluid under pressure for actuating said feed mechanism and said traverse motor,
  - (d) means to prevent the operation of said traverse motor from adversely affecting said feed mechanism comprising means operable when said feed mechanism reaches advanced position to disconnect said feed mechanism from said common supply of fluid under pressure.
8. In a grinding machine,
- (a) a feed mechanism,
  - (b) a traverse motor,
  - (c) a common supply of fluid under pressure for actuating said feed mechanism and said traverse motor,
  - (d) and means operable when said feed mechanism is in advanced position to disconnect said feed mechanism from said common supply of fluid under pressure,
  - (e) the means for disconnecting said feed mechanism from the common supply of fluid under pressure being a valve actuated by exhaust pressure from said feed mechanism and normally held by said exhaust pressure in position to connect both the feed mechanism and the traverse motor to said common supply of fluid under pressure.
